ELECTRIC HOT PLATE OR THE LIKE

Alan W. Duncan, Itasca, Ill., assignor to Sears, Roebuck and Co., Chicago, Ill., a corporation of New York

Filed June 17, 1963, Ser. No. 75,359

Term of patent 7 years

(Cl. D81—10)

Fig. 1.

Fig. 2.

FIG. 1 is a perspective view of an electric hot plate or the like in closed position, showing my new design; and

FIG. 2 is a perspective view thereof, with the cover in open position.

The dominant features of my design reside in the portions shown in full lines. The undisclosed side is substantially the same as the side shown and the bottom and rear portions not shown are flat and plain.

I claim:

The ornamental design for an electric hot plate or the like, as shown and described.
